US00D975108S

(12) **United States Design Patent** (10) Patent No.: **US D975,108 S**
(45) Date of Patent: ** *Jan. 10, 2023

(54) **DISPLAY SCREEN OR PORTION THEREOF WITH GRAPHICAL USER INTERFACE**

(71) Applicant: **Apple Inc.**, Cupertino, CA (US)

(72) Inventors: **Robert W. Baker**, Cupertino, CA (US);
Sebastian Boltz, Elmshorn (DE);
Joshua W. Decker, San Francisco, CA (US); **Soeren Kelling**, Rellingen (DE);
Ole Lagemann, Rellingen (DE)

(73) Assignee: **Apple Inc.**, Cupertino, CA (US)

(*) Notice: This patent is subject to a terminal disclaimer.

(**) Term: **15 Years**

(21) Appl. No.: **29/753,395**

(22) Filed: **Sep. 30, 2020**

Related U.S. Application Data

(63) Continuation of application No. 29/682,669, filed on Mar. 7, 2019, now Pat. No. Des. 900,846, which is a continuation of application No. 29/624,545, filed on Nov. 1, 2017, now Pat. No. Des. 847,841.

CLAIM

The ornamental design for a display screen or portion thereof with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

The sole FIGURE shows a display screen or portion thereof with graphical user interface showing our new design.

The peripheral dashed broken lines illustrate a display screen or portion thereof, and form no part of the claimed design.
